UNITED STATES PATENT OFFICE.

IVAR RENNERFELT, OF DJURSHOLM, SWEDEN.

ELECTRIC-ARC FURNACE.

1,294,830.

Specification of Letters Patent. Patented Feb. 18, 1919.

Application filed August 24, 1916. Serial No. 116,637.

To all whom it may concern:

Be it known that I, IVAR RENNERFELT, a subject of the King of Sweden, residing at Djursholm, in the Kingdom of Sweden, have 5 invented a new and useful Improvement in Electric-Arc Furnaces, of which the following is a specification.

Electric arc furnaces are previously known which are provided with a heating chamber 10 for receiving the material to be heated and with an electric arc chamber separated from the said heating chamber, in which electric arc chamber the electric arcs serving for heating the material are generated. In furnaces of this kind the heat will of course be better utilized if the generated arcs are made to contact with the wall between the electric arc chamber and the heating chamber, that is to say, with the wall of the retort in case the 15 heating chamber consists of a retort placed in the electric arc chamber. It has already been proposed to have the retort form one of the electrodes and to generate the arc or arcs between the retort and one or more other electrodes in the electric arc chamber. Such furnaces are encumbered with the disadvantage, however, that when starting the furnace, when the electrodes must be moved into contact with the retort or the wall and, accordingly, the resistance becomes comparatively small, a strong rush of current will be formed, and for this reason such furnaces 20 are not well adapted for use on circuits with constant tension, such as a lighting circuit, 25 without the use of damping coils, starting resistances, or the like.

The primary object of the present invention is to avoid this disadvantage and to make the furnace capable of being used directly on, for instance, lighting circuits without the use of any special starting devices. For this purpose the invention is broadly characterized by this that the electric arc chamber and the chamber or chambers in 30 which the material is heated, are separated by means of a preferably refractory and pulverized resistance material and that the electrodes are arranged in such manner in the electric arc chamber that the electric arcs formed by the electrodes are closed by the said resistance material. The said resistance material consists preferably of finely

pulverized graphite or coke and it is so dimensioned that the principal generation of heat is effected by the arcs. When the furnace is started in cold state, however, the 55 said resistance material serves as a starting resistance which prevents the generation of strong rushes of current, thus making it unnecessary to use any special apparatus for 60 the starting. As the resistance of the material is decreased when heated the electrodes are withdrawn, thus insuring a smooth and easy starting of the furnace. Accordingly, 65 the present invention renders possible the use of electric current as a source of heat also in such cases where the amount of energy available is comparatively small, and the conditions do not allow, even temporarily, the consumption of current to exceed certain limits. 70 By the use of the resistance material the heat will also be more uniformly distributed in the heating chamber.

In order to render possible a continuous heating without the furnace having to be 75 wholly or partly taken to pieces at intervals, apertures are provided in the walls or in the bottom of the furnace hearth, through which apertures the material to be heated may be introduced in the furnace. Graphitization 80 of carbon electrodes may thus be performed in such manner that they are introduced at one side of the furnace and removed at the other side thereof after having been heated by the heat from the electric arcs during a 85 sufficiently long time. If the electrodes are slowly moved through said apertures, they may be preheated and cooled simultaneously 90 in the bottom or walls of the hearth without appreciable oxidation, provided that the bottom and walls are made sufficiently thick 95 for the purpose. Below the electric arcs a suitable quantity of preferably pulverized carbon or graphite is placed as contact material. Fresh carbon or graphite powder is 100 preferably introduced through apertures in the vault of the furnace or through the openings for the electrodes. In order that the powder shall not prevent the feeding forward of the electrodes to be treated, it is suitable to provide channels covered by slabs, in the bottom of the furnace, in which channels the electrodes are fed forward during the process of graphitization. According to

a modification of the invention the bottom of the furnace may also be movable in a horizontal or vertical direction for the purpose of making it possible to introduce beneath the arcs a charge of many electrodes simultaneously.

According to the invention the furnace may also be constructed in such manner that the heating chamber, for instance a retort or 10 a cupel-furnace, is completely embedded in the resistance or contact material. By also embedding a contact in the material and by supplying current to this contact heat may also be generated in the resistance material 15 in addition to the heat generated by the arcs. The retort may be made from graphite or carbon, whereby an increased conduction of heat from the arc zone to the interior of the retort is obtained owing to the high 20 thermal conductivity of the material used. A further advantage is that the retort will not be damaged or melted by superheating the same. The retort may, of course, also be made from other refractory materials, 25 such as carborundum, magnesite, fire-clay, and so forth. It may be constructed round, square, or any other shape desired. A number of retorts embedded one over the other or side by side, may also be used, if desired, 30 whereby the material may be transferred gradually from retorts of lower temperatures to retorts having higher temperatures. If desired, the retort may be provided with means for circulation of gases.

35 In the accompanying drawings a few embodiments of furnaces suitable for performing the present process, have been shown by way of example. Figure 1 shows a vertical longitudinal section of a furnace provided 40 with three electrodes, in the bottom of which furnace there are channels for receiving the carbon electrodes or other material to be heated. Fig. 2 shows a vertical cross section of the same furnace on the line II-II 45 in Fig. 1. Fig. 3 shows a vertical cross section of a furnace as shown in Fig. 1 but provided with a cylindrical bottom in which there is a number of channels. Fig. 3 may also be regarded as a horizontal cross section 50 of a furnace having a vertical shaft or chamber. Fig. 4 shows a vertical cross section, and Fig. 5 a vertical longitudinal section of a third embodiment, of which Fig. 6 shows a detail.

55 Referring to Figs. 1 and 2, the furnace is shown provided with vertical electrodes 1 projecting into the same through apertures in the vault 2 and insulated from the same. These electrodes generate arcs 3 contacting 60 with carbon powder 4 on the bottom 5. The bottom and the walls of the hearth are made from a very refractory material, preferably carbon brick. In the bottom there are long channels 6 into which the charge 7 may be in-

65 troduced at one side of the furnace, and may be removed at the other side thereof at which time it may be simultaneously pre-heated and cooled. The interior carbon lining of the furnace is surrounded by magnesite brick or the like and is well insulated 70 by means of asbestos or other suitable material to prevent heat loss. The walls of the furnace are suitably provided with apertures 8 for introducing carbon powder, when required, and for examining the interior of the furnace. The apertures 9 through which the electrodes 1 project into the furnace, are of comparatively large size 75 in order to prevent discharges from the electrodes through the conducting brickwork. 80

In the furnace shown in Fig. 3 the bottom of the hearth is of cylindrical shape and in the bottom and the walls there is provided a plurality of channels 10.

The furnace illustrated in Figs. 4-6 is provided with an electrode or arc chamber 11 and an electrode 12 projecting into the same. The electrode generates an arc 13 contacting with a more or less finely divided conductor 14. Below the arc a chamber 15 is arranged in the conductor 14, this chamber being formed, in the instance shown, by means of a retort or a cupel-furnace 16. Below this cupel-furnace 16 there is a conductive mass or body 17 in which there is an electrode 18 or other contact for the current forming the arc 13. The walls 19 of the electrode chamber 11 and of the chamber 15 are made from a very refractory material, such as magnesite, carbon brick, chamotte, carborundum, or the like. For feeding the electrode 12 downward there is arranged on the furnace a screw 21 and hand-wheel 20 which actuates an arm 22 connected at 23 in any suitable manner to the electrode 12. 100 105

I claim:

1. In an electric arc furnace, the combination of an electric arc chamber, a heating chamber for receiving the material to be heated, a partition consisting of a preferably refractory and pulverized resistance material between said chambers, and electrodes projecting into said electric arc chamber in such manner that the electric arcs formed by the electrodes are closed by 110 115 the said refractory resistance material.

2. In an electric arc furnace, the combination of an electric arc chamber, a heating chamber for receiving the material to be heated formed in the bottom of said electric 120 arc chamber, a preferably refractory and pulverized resistance material covering the bottom of said electric arc chamber, and electrodes projecting into said electric arc chamber in such manner that the electric arcs formed by the electrodes are closed by the 125 said refractory resistance material.

3. In an electric arc furnace, the combi-

nation of an electric arc chamber, a heating chamber for receiving the material to be heated, a preferably refractory and pulverized resistance material surrounding said heating chamber and forming a partition between said heating chamber and said electric arc chamber, electrodes projecting into

said electric arc chamber in such manner that the electric arcs formed by the electrodes are closed by the said refractory resistance material, and an electric contact embedded in said resistance material.

IVAR RENNERFELT
